United States Patent Office

Des. 219,416
Patented Dec. 8, 1970

219,416

TOTE BAG

Leo A. Wonsavage, 1075 E. 76th St.,
Cleveland, Ohio 44103

Filed Aug. 7, 1969, Ser. No. 18,574

Term of patent 14 years

Int. Cl. D3—99

U.S. Cl. D87—1

FIG. 1

FIG. 2

FIG. 3

FIG. 4

FIG. 1 is a front elevational view of a tote bag showing my new design, the side opposite thereto being identical;

FIG. 2 is a side elevational view thereof;

FIG. 3 is a bottom plan view; and

FIG. 4 is a top plan view.

I claim:

The ornamental design for a tote bag, substantially as shown and described.
